UNITED STATES PATENT OFFICE.

FELIX PETER SKORNICKI, OF JERSEY CITY, NEW JERSEY.

CLOTHES-LINE PULLEY.

SPECIFICATION forming part of Letters Patent No. 432,334, dated July 15, 1890.

Application filed July 3, 1889. Serial No. 316,394. (No model.)

To all whom it may concern:

Be it known that I, FELIX PETER SKORNICKI, of Jersey City, in the county of Hudson and State of New Jersey, a citizen of the 5 United States, have invented certain new and useful Improvements in Clothes-Line Pulleys, of which the following is a specification.

This invention relates to an improved 10 clothes-line supporter by which the clothes may be hung on both lengths of the line instead of along one length of the same only.

In the accompanying drawings, Figure 1 15 represents a side elevation of my improved clothes-line supporter. Fig. 2 is a horizontal section of the same, drawn on a larger scale, on line $\alpha\alpha$, Fig. 1; and Fig. 3 is a side elevation, partly in vertical section of one pulley, drawn on a still larger scale.

20 Similar letters of reference indicate corresponding parts.

Referring to the drawings, A represents a clothes-line, which is stretched tightly around two pulleys B B, which turn on spindles C C, 25 which are supported by curved bracket-arms D. The bracket-arms D are respectively applied to the window-easing by any suitable mechanism, preferably by means of supporting hooks and links, as shown in the drawings, so that a certain yielding support is obtained, and to a supporting-post.

The pulley B consists of an elongated body

provided with a shallow circumferential groove a for the clothes-line, and with a hand-wheel disk E below said groove, which serves 35 as a driving-wheel and as a guide for the clothes, said body being rounded at c above said groove and tapered at d above the rounded part. The enlarged disk at the lower end of the pulley-body serves the 40 double purpose of a hand-wheel and a guide for the clothes, and owing to the elongated body and shallow groove the clothes-pins which clamp the clothes on the line readily pass around the pulley with the line and 45 clothes.

Having thus described my invention, I claim as new, and desire to secure by Letters Patent—

A clothes-line pulley consisting of an elongated body provided with a shallow circumferential groove for the clothes-line and with a hand-wheel disk below said groove, which serves as a driving-wheel and as a guide for the clothes, said body being rounded and tapered above the groove, substantially as described.

In testimony that I claim the foregoing as my invention I have signed my name in presence of two subscribing witnesses.

FELIX PETER SKORNICKI.
